UNITED STATES PATENT OFFICE

KARL E. BERNO, OF DETROIT, MICHIGAN

DESIGN FOR A CLOCK FRAME

Application filed April 25, 1932. Serial No. 43,594. Term of patent 7 years.

• *To all whom it may concern:*

Be it known that I, KARL E. BERNO, a citizen of the United States, residing in the city of Detroit, county of Wayne, and State of Michigan, have invented a new, original, and ornamental Design for a Clock Frame, of which the following is a specification, reference being had to the accompanying drawing, forming part thereof.

In the drawing, Figure 1 is a front view of the clock frame showing my new design;

Figure 2 is a side elevation of the clock frame shown in Figure 1.

My design is characterized by the frame mouldings and borders together with the relative positions of the clock face borders and the ornamental picture.

I claim:

The ornamental design for a clock frame substantially as shown and described.

In testimony whereof, I affix my signature, this 22nd day of April, 1932.

KARL E. BERNO.
